UNITED STATES PATENT OFFICE.

WILLIAM J. PATTERSON, OF ELLWOOD CITY, PENNSYLVANIA.

DESIGN FOR A LAMP-CHIMNEY.

SPECIFICATION forming part of Design No. 23,675, dated October 2, 1894.

Application filed August 23, 1894. Serial No. 521,132. Term of patent 7 years.

To all whom it may concern:

Be it known that I, WILLIAM J. PATTERSON, a citizen of the United States, residing at Ellwood City, in the county of Lawrence and State of Pennsylvania, have invented or produced a new and original Design for Lamp-Chimneys, of which the following is a specification.

The object of this design is to provide a novel and distinctive lamp chimney, which presents a handsome, peculiar, and characteristic appearance to the eye.

The design consists in a lamp chimney comprising a true cylinder base portion, a globular body portion formed like a truncated conoid uniformly and gradually tapered into a contracted annular neck, which uniformly and gradually swells in an upward and outward direction, the swelled portion extending vertically into a circular portion that gradually decreases in diameter to its top edge.

The invention is illustrated by the accompanying drawings, in which—chimney; and, Fig. 2, is a top plan view of the same.

In the accompanying drawings, the numeral 1 indicates the true cylinder base portion, 2 the globular body portion formed like a truncated conoid which tapers uniformly and gradually, as at 3, into a contracted annular neck 4. This neck uniformly and gradually swells outward in an upward direction, as at 5, and the swell portion 5 extends vertically 35 into a circular portion 6, which gradually decreases in diameter to its top edge 7.

The chimney is truly circular at all points, and the whole presents a handsome, ornamental, and distinctive appearance. 40

What I claim is—

The design for a lamp chimney, as herein shown and described.

In testimony whereof I have hereunto set my hand and affixed my seal in presence of 45 two subscribing witnesses.

WILLIAM J. PATTERSON. [I. S.]
